UNITED STATES PATENT OFFICE.

JOHN C. BLOOM, OF KALAMAZOO, MICHIGAN, ASSIGNOR TO THE EMERSON,
TALCOTT & COMPANY, OF ROCKFORD, ILLINOIS.

MOWING-MACHINE.

SPECIFICATION forming part of Letters Patent No. 369,225, dated August 30, 1887.

Application filed November 15, 1886. Serial No. 218,856. (No model.)

To all whom it may concern:

Be it known that I, JOHN C. BLOOM, a citizen of the United States, residing at Kalamazoo, county of Kalamazoo, and State of Michigan, have invented a new and useful Mowing-Machine, of which the following is a specification.

The object of this invention is to provide a mowing-machine with certain means whereby the weight of the cutter-bar and coupling-arm to which it is hinged is largely or entirely sustained by the draft-power of the team.

In the drawings forming a part of this specification, Figure 1 is a plan view of a mowing-machine to which the invention is applied; and Fig. 2 is an enlarged detail view, in perspective, of the draft devices.

The tongue B and the cutter-bar D are broken in both figures of the drawings. It is well known that owing to the great weight of the cutter-bar D and coupling-arm E, especially those of extra length, a great friction is caused with the ground, causing the machine to draw hard. Besides, it requires a great exertion to raise them with the lever L, or to swing the cutter-bar D upward on its hinge O.

In carrying my invention into effect I employ an equalizer, c, with which the whiffle-tree C is attached at r. A plate, v', having a slot elongated on a line with the tongue B, is secured to said tongue. The equalizer c is pivoted in said slot at f, so as to allow it to swing on said pivot and to move forward and back therewith. The forward end of the draw-rod a is pivotally connected with the inside end of the equalizer c in one of a series of holes at said end. The rear end of the rod a is anchored to the tongue at v. A pulley, x, is attached to the tongue, and beneath it a pulley, s, is attached to the coupling-arm E. At i is an arm projecting upward from the finger-bar D. A chain, u, or cable is attached to the outside end of the equalizer in one of a series of holes, and from thence passes around the pulleys x s, and attaches in one of a series of holes in the arm i. Thus by applying draft-power to the equalizer the machine is propelled, and the weight of the arm E and bar D is sustained by said draft-power, or so much of the weight thereof as may be desir-

able, the degree being controlled by changing the point of attaching the rod a and chain u with the ends of the equalizer c. By changing the point of attaching the chain u to arm i the degree of leverage on the finger-bar D is 55 altered. This chain may be attached directly to the finger-bar.

The upward movement of the finger-bar D is limited by a stop, e, on the chain u, which may be advantageous in case of a sudden start 60 or spring of a fractious team.

I am aware that the coupling-arm has been connected by a chain or rod to a movable slide with which the whiffle-tree was attached, but for a different purpose—viz., to brace the finger-bar against tilting to the rearward. In said prior construction no equalizer was employed (a very important feature in the present instance) to adjust the leverage of the draft-power in heavy and light grass and on 70 hard smooth ground and soft or rough ground.

I am also aware that the chain u in a similar relation with the parts D E s x has been heretofore attached at the forward end to a spiral spring, which spring was attached to the tongue, 75 thus depending upon the stiffness and strength of the spring to sustain the weight of the finger-bar.

An important advantage, among many which need not be herein mentioned, why the leverage of the draft-power is preferable to that of a spring is illustrated by the following facts: The heavier the grass or the harder it cuts the greater the tendency of the finger-bar to hug the ground. In such case the draft-strain 85 is greater and prevents the finger-bar from hugging the ground. So, if the wheels A enter a hollow, the draft-power is increased, and hence an increase in leverage to raise up on the cutter-bar, thus lessening the liability of 90 the guards to enter the elevated ground in front of them. In brief, so finely can the parts be adjusted for varying fields and weight of grass in relation to the draft-power that the leverage of said power on the coupling-arm 95 and finger-bar automatically adjusts itself or conforms to the needed requirements as the machine moves around the field. It will further be observed that the shoe end of the arms E and the shoe end of the finger-bar (said 100

end of the finger-bar is broken away in the drawings) are both sustained on a like horizontal plane at the same time by the draft-power.

5 It will be understood that I do not herein claim the stop *e* on the draft-chain *u*, as such is claimed in another application, Serial No. 225,661, filed by me January 27, 1887.

Having thus described my invention, what 10 I claim is—

In a mowing-machine, the combination, with the tongue or draft-frame, the coupling-arm, and the finger-bar, of the equalizer pivotally connected with said draft-frame and capable 15 of moving bodily forward and back thereon, the draw-rod attached to one end of the equal-

izer and secured to the draft-frame, the guide-pulleys, one on the draft-frame and the other on the coupling-arm, and the chain or flexible connection attached to the other end of the 20 equalizer passing over the pulley on the frame and under the one on the coupling-arm and attached to an arm on the finger-bar, as and for the purpose set forth.

In testimony of the foregoing I have here- 25 unto subscribed my name in presence of two witnesses.

JOHN C. BLOOM.
